UNITED STATES PATENT OFFICE

RAY R. HUTCHESON, OF RICHMOND HILL, NEW YORK, ASSIGNOR TO WM. DEMUTH & CO., A CORPORATION OF NEW YORK

DESIGN FOR A TABLE LIGHTER

Application filed March 6, 1931. Serial No. 38,977. Term of patent 7 years.

To all whom it may concern:

Be it known that I, RAY R. HUTCHESON, a citizen of the United States of America, and a resident of Richmond Hill, county of Queens, and State of New York, have invented a new, original, and ornamental Design for Table Lighters, of which the following is a specification, reference being had to the accompanying drawings, forming a part hereof.

In the drawings:

Figure 2 is a fragmentary view of the head portion with the parts opened up to disclose the lighter mechanism.

The design is characterized by a figure of an armored knight with head armor which opens to permit access to a lighter mechanism for lighting cigars, cigarettes and the like.

I claim:

The ornamental design for a table lighter substantially as shown and described.

RAY R. HUTCHESON.
